ENCLOSURE

Joseph A. Volk, Wilton, Conn.

Application September 5, 1940, Serial No. 355,479

6 Claims. (Cl. 135—5)

This invention relates to temporary enclosures, and particularly to such an enclosure intended for use in a store to provide a compartment adjacent to the entrance door and into which goods may be delivered outside of business hours and while protecting goods already in the store from access from within the enclosure.

In my Patent No. 2,152,368 for Enclosure granted March 28, 1939, there is illustrated an enclosure for this purpose formed of a series of curtains mounted on rollers near the ceiling of the store and which may be let down to form the enclosure and rolled up out of the way to inoperative position when not required. This arrangement requires lacing or other fastening means for joining the adjacent edges of the curtains when they are unrolled in order to prevent access to the remainder of the store from within the enclosure between the edges of the curtains, and this fastening means must be released to enable the curtains to be rolled up.

An object of the present invention is to avoid the necessity of employing such fastening means which must be secured and released after the enclosure is positioned for use and before it can be removed, respectively.

A further object is to provide for adjustment of the enclosure to the height of the ceiling so that the enclosure parts may be made of standard dimensions, the adjustment for height of ceiling being made once and for all when the enclosure is installed.

Further improvements and advantages will appear from a more complete description of an embodiment of the invention shown in the accompanying drawings in which

Figure 1 is a perspective view of the enclosure in operative position, the ceiling and other portions of the store interior being omitted.

Figure 2 is a plan view of the front portion of a store showing two possible arrangements of the enclosure.

Figure 3 is a fragmentary side elevation of one portion of the enclosure adjacent to the ceiling of the store.

Figures 4 and 5 are detail sections on lines 4—4 and 5—5, respectively, of Figure 3.

Figure 6 is a fragmentary side elevation of one end portion of the enclosure illustrating its mounting.

Figure 7 is a detail section on line 7—7 of Figure 6.

Figure 8 is a detail section on line 8—8 of Figure 1.

As shown in Figure 1, the enclosure comprises

5 a single curtain 1 which may be extended around an area of the floor 2 of the store and extend substantially from this floor upwardly closely adjacent to the ceiling, thereby to prevent a person within the enclosure when it is in operative position having access to articles within the store outside of the enclosure. As shown, the upper edge portion of the curtain is divided part way down as at 1a to form a plurality, of at least 10 three, sections for the curtain. Each of these sections has its top edge secured to an elongated roller 3, the rollers being angularly related so as to substantially follow the area to be enclosed and forming upper edges of straight side walls 15 for such area angularly related to each other. As shown in Figure 6, the ends of the rollers 3 which are positioned adjacent to the ends of the curtain and adjacent to a wall 4 of the store within which is positioned a doorway 5, are held 20 in position adjacent to the ceiling of the room as by the angle rods 6. One upper end of such rod 6 may be extended through a hole in the roller 3 and the lower portion, laterally offset as at 7, may be supported in a pair of ears 8 in a bracket 25 9 secured to any suitable portion of the side wall 4, as for example, to a side sill 10 of the door opening. The opposite ends of these rollers 3 and also the ends of adjacent rollers back from the wall 4 may be carried by suitable brackets 12, 13 forming portions of gear casings 14 and 15, respectively. These gear casings may be provided with hangers 17, each hanger having a horizontal perforation for the reception of a bar 18, the ends of which may be supported in 30 ring bolts 19 depending from ceiling beams 20 of the store. Since such ceiling beams may be arranged differently in the various buildings, the bar 18 may be of sufficient length to be supported by the rings 19 for a wide variation of 35 spacing of the beams 20, or if desired, bars 18 of various lengths, which may be selected in accordance with the beam spacing as it is found in any particular store, may be employed. The hangers 17 may be adjustable lengthwise of the bars 18 in accordance with the lengths of the 40 shafts 3 and with curtain operating rollers, to be later described, and be secured in fixed positions as by set screws 21.

In any given installation the curtain sections 45 will be wound up on the rollers 3 to such an extent that the lower edge of the curtain will be located close to the floor of the store when the enclosure is in its lowered position, but as the amount of this winding of the top edge of the curtain sections is fixed in any particular installa-

tion, the engagement of the supporting bracket rod 6 with the rollers will prevent further rotation thereof, so that after installation the curtain will be supported as though it were cut to the height required for the particular installation. The cut portions 2 which define the curtain sections will then be closed as by lacings 25 or other suitable means, from the lower ends of the cut portions upwardly to as close to the rollers 3 as is convenient so as to close up as much of these openings as possible to prevent access to articles in the store from within the enclosure through these openings. While the curtain is shown divided at its top into three sections, it might be divided into more if desired, with a roller 3 for supporting each section.

As before noted, the gear casings 14 and 15 are employed to support and interconnect for simultaneous rotation, means for lifting the lower edge of the curtain from the floor when it is desired to remove the enclosure from operative condition. The gear casing 14, as shown in Figure 4, comprises a pair of angularly related wall members 30 and 31 secured together as by screws 32, and a zigzag back plate 33 secured to the remote edges of the plates 30 and 31 as by screws 34. These plates define a pair of angularly related chambers 36 and 37 for the reception of intermeshing bevel gears 38 and 39, respectively, carried by shafts 40 and 41. The shaft 40 is journaled in the plate 30 and has secured to its outer end a socket member 41 within which is secured as by the cotter pin 42 the rounded end 43 of a plug 44 which closes one end of a tubular roller 45. This head 43 is provided with flat faces 46 so spaced that the plug 44 is substantially non-rotative about its axis with respect to the socket 41, although it is permitted a considerable freedom of universal movement with respect to this socket as far as this is allowed by the cotter pin 42. This permits the angularity of the roller 45 with respect to the shaft 40 to be varied quite widely and yet affords a rotating driving connection between this shaft 38 and the roller 45.

The shaft 41 is journaled in the plate 31 and has secured to its outer end outwardly of the gear casing, as by a cotter pin 48, a plug 49 which closes the open end of a tube 50 serving as a portion of another roller. The opposite end of this tube 50 is closed off by a plug 51 which may be similar to the plug 49, and this plug 51 is connected as by the cotter pin 52 to a shaft 53 journaled in the gear casing 15. This gear casing 15 is provided with means by which rotation may be imparted to the roller 50. For this purpose the shaft 53 has a worm gear 54 secured to its inner end with which meshes a worm 55 on a shaft 56 arranged in a substantially vertical position and as shown in Figure 3 having a hook 57 secured to its lower end. This permits engagement with a similar hook or an eye on a hand operated crank rod (not shown) by the rotation of which the shaft 56 may be rotated. The gear casing 15 also has journaled therethrough a shaft 60 having a worm gear 61 thereon which also meshes with the worm 55, so that as this worm is rotated not only is the roller 50 rotated but the shaft 60 is also rotated. This shaft 60 may have secured at its outer end a socket 64 similar to the socket 41 and to which may be secured in a similar manner an end closure plug 62 similar to the plug 44 for a tubular roller 63. The gear casing 15 may be arranged at any desired corner of the enclosure and serves to drive rollers 50 and 63 with the same drive member, while the roller

5 44 is also driven by the same means through the gears 38 and 39 within the gear box 33. While three winding rollers or shafts 45, 50 and 63 are shown herein, there might be more geared together for simultaneous rotation, where an enclosure having more than four sides is desired.

10 As shown in Figure 1, the drive roller 63 extending from the gear box 15 is journaled at its opposite end as on a trunnion 65 which is held between the ears 8 of the bracket 9 by the member 6 which passes therethrough. These shafts 45, 50 and 63 have secured thereto at suitable points flexible members such as cables 66 which may be wound on these shafts by rotation thereof, these cables being secured at their lower ends to rigid members 67 to which the lower edge of the curtain is secured. As shown best in Figure 6, these rigid members may be pipes. The forward ends of these members 67 which terminate adjacent to the wall member 4 may be provided with loops 68 through which extend upright posts 69. The upper end of each post 69 is shown as provided with an eye 70 which engages a screw eye 71 carried by the bracket 9. This permits the lower end of either of the upright bars 69 to be swung outwardly from adjacent to the wall member when desired, permitting the adjacent end of the bar 67 to be lifted, the ring member 68 sliding upwardly on the upright 69, into the position shown in dotted lines in Figure 1, which permits a person to pass from the interior of the store into the enclosure between the uprights 69 and the wall member, whereupon he may allow the curtain to drop at its forward end and the upright 69 to resume its upright position. In this position the parts may be locked as by means of a padlock 71, the hasp of which may pass through the ring 68, a ring 72 secured to the lower end of the upright 69 and a perforated angle bracket 73 which may be secured to a fixed part of the store, such as the wall or floor or both. It will be understood that one of these padlocks is provided for the lower end of each of the uprights 69. The rear bar or bars 69 which do not approach the 15 wall of the store may be anchored down to the floor by means such as shown in Figure 8. Each anchorage comprises a set screw socket 75 embedded in the floor. Cooperating with this socket is a bolt 76 which may pass through the rear member 67 and an eyelet 77 at the end of the side bar 67, this construction permitting the forward end of the side bar to be lifted as previously described. The bolt 76 may have a lock nut 78 threaded thereon and a disk shaped shield 79 enclosing this nut may be employed to prevent access thereto from within the enclosure when the curtain is down. For the purpose of further preventing unauthorized loosening of a screw 76 and for indicating that the enclosure has been 20 tampered with if it should be so loosened, each of the screws 76 may have a polygonal socket 80 in its upper end into which may be extended an actuating crank 81. The two cranks at the back corners of the enclosure may be tied together by a bar 82 having at each end a hole to take over the upper end of the handle 81. These holes are preferably spaced differently from the crank centers, as shown shorter, so that an attempt to turn one of the cranks will cause both to lock with the bar. Should the bar 82 be found detached, it will be clear that the enclosure has been tampered with.

25 In order to retain the curtain in a neat folded condition when its lower end is lifted by rotation of the winding rolls 45, 50 and 63, the cords 66

may pass from side to side of the curtain through spaced eyelets or grommets 85 set in holes through the curtain in vertical series. In order that the forward edges of the curtain may be held close to the wall member so that access may not be had between these edges and the wall member to articles within the store, the forward edges of the curtains may be provided with a series of eyes 88 as shown in Figure 7 slidable on the uprights 69. As shown these eyes may have forked extensions 89 which may be crimped about an enlarged edge binding 90 of the curtain which may be formed by folding its edge over about a flexible filler strip 91. It will be noted that the connections at the corners of the enclosure at the supporting bars 3, at the rigid lower members 67, and between the ends of the winding rolls 45, 50 and 63 are of considerable flexibility so as to permit the enclosure to be conformed readily to the various conditions which may be encountered in different buildings, permitting the curtain sections to be associated with each other at various angles. For example, as shown in Figure 2 in full lines, the sides of the enclosure extend backwardly from the door casing substantially perpendicularly thereto and the back wall portion of the curtain is substantially parallel to the front wall of the store within which the entrance door is positioned. However, the enclosure may be arranged in many different shapes, another of which is illustrated in dotted lines in Figure 2, in which the sides of the enclosure are arranged at acute angles to the forward faces of the store portions to which they are secured and make an obtuse angle with the back wall member. This possibility of considerable variations in the angular relations of the wall portions of the enclosure make it possible to employ the same equipment in a great variety of relations, and with the further adjustment for height of ceiling provided by rolling the top edge of the curtain on the supports 3 to the desired extent, provides a single structure of substantially universal application to the various conditions which may be met in practice. In each case the enclosure may shut off a portion of the store to which access may be had by a store door, from the remainder of the store, so that goods may be delivered therein outside of business hours. When the store is to be opened, this enclosure may be moved out of the way by a person having a key by which the enclosure may be unlocked, whereupon the goods delivered within the enclosure may be placed with the store stock, and the enclosure presents no obstruction to normal use of the store.

From the foregoing description of an embodiment of this invention, it should be evident to those skilled in the art that various changes and modifications might be made without departing from the spirit or scope of this invention as defined by the appended claims.

I claim:

1. An enclosure comprising a single curtain, means for supporting said curtain adjacent to the ceiling of a room to enclose an area extending from a wall of said room having a door therein, said curtain supporting means including a plurality of rollers arranged substantially end to end and some at least angularly related to an adjacent roller for supporting the upper edge of said curtain, the upper portion of said curtain being divided into sections, each of said sections being wound on one of said rollers to an extent to permit the lower edge of said curtain to be posi-

tioned adjacent to the floor of the room, and means for lifting the lower edge of said curtain from said floor substantially simultaneously at a plurality of positions distributed around said area.

2. An enclosure comprising a single curtain, means for supporting said curtain adjacent to the ceiling of a room to enclose an area extending from a wall of said room having a door therein, 10 said curtain supporting means including a plurality of rollers arranged substantially end to end and some at least angularly related to an adjacent roller for supporting the upper edge of said curtain, the upper portion of said curtain being divided into sections, each of said sections being wound on one of said rollers to an extent to permit the lower edge of said curtain to be positioned adjacent to the floor of the room, means for releasably securing said sections together in said divided portion from the lower end of the division upward adjacent to said rollers, and means for lifting the lower edge of said curtain from said floor substantially simultaneously at a plurality of positions distributed around said area.

25 3. An enclosure comprising a curtain, means supporting said curtain with reference to a wall member and a floor to define with said wall member an enclosed area of said floor, said supporting means including a normally upright rigid member hingedly supported above its lower end adjacent to said wall member, means carried by an end of said curtain slidably securing said end to said rigid member, a second rigid member, means for hingedly supporting said second rigid member at the lower portion of said curtain remote from said wall member with said second member normally extending adjacent to said wall member adjacent to the floor of said enclosure and to which the lower edge of said curtain is secured, and means for locking the lower end of said normally upright member and said second member together adjacent to said floor and wall member.

4. An enclosure comprising a curtain, a plurality of elongated members arranged in end to end angular relation adjacent to the ceiling of a room and to which the upper portion of said curtain is secured, a plurality of rigid members arranged in end to end relation and normally close to the floor of said room and to which the lower edge of said curtain is secured, the ends of said curtain extending adjacent to a wall member of said room having a doorway therethrough through which access may be had to the interior of said enclosure, bars hinged at their upper ends to said wall member and to which the ends of said curtain are slidably secured, means engaging the lower portion of said curtain at spaced points therealong for lifting said curtain above said floor, means for releasably securing the adjacent ends of said rigid members to said floor, and means for locking the lower ends of said bars and the adjacent ends of said rigid members adjacent to said floor and wall.

5. An enclosure comprising a curtain, a plurality of elongated members arranged in end to end angular relation adjacent to the ceiling of a room and to which the upper portion of said curtain is secured, a plurality of rigid members arranged in end to end relation and normally close to the floor of said room and to which the lower edge of said curtain is secured, the ends of said curtain extending adjacent to a wall member of said room having a doorway therethrough through which access may be had to the interior

of said enclosure, rollers supported adjacent to said elongated members, cords secured to said rollers and extending from side to side of said curtain through vertically spaced openings therethrough and secured at their lower ends to the lower portion of said curtain, said cords being arranged in spaced relation lengthwise of said curtain, means for simultaneously rotating said rollers to thereby raise said curtain from said floor, and means for retaining the ends of said curtain adjacent to said wall member.

6. An enclosure comprising a curtain, means

for supporting the upper portion of said curtain adjacent to the ceiling of a room, a rigid frame member to which the lower edge of said curtain is secured and normally close to the floor of said room and at least partly defining an area of said floor, elements journaled in said frame member for threaded engagement in said floor and having crank portions, and a locking bar having holes to receive said crank portions spaced apart a distance different from the spacing of said elements.

10

JOSEPH A. VOLK.
